UNITED STATES PATENT OFFICE.

HARRY E. LA BOUR, OF CHICAGO, ILLINOIS.

PUMP.

Application filed March 7, 1921. Serial No. 450,349.

To all whom it may concern:

Be it known that I, HARRY E. LA BOUR, a citizen of the United States, residing at Chicago, in the county of Cook and State 5 of Illinois, have invented a certain new and useful Improvement in Pumps, of which the following is a full, clear, concise, and exact description, reference being had to the accompanying drawings, forming a part of 10 this specification.

My invention relates to pumps, more particularly to centrifugal pumps.

In centrifugal pumps it is desirable to have a pump which does not become air 15 bound, and it is furthermore desirable to have as little end thrust on the shaft of the pump as possible. A further desideratum is high efficiency and the ability to deliver a relatively high pressure.

My invention accomplishes the above 20 desired functions in a simple and effective manner, and in addition I have found that the pump, so long as it has a liquid seal, is able to exert sufficient suction when 25 running with air in the pump casing to raise water a height of five or six feet.

Further and more specific advantages of 30 my invention will be advanced from the following detailed description.

In the accompanying drawings, which 35 illustrate an embodiment of my invention:

Figure 1 is a vertical cross sectional view of a pump embodying my invention;

Figure 2 is an elevational front view of 40 the runner and rear plate, with the front plate removed;

Figure 3 is a side elevational view of a 45 pump and motor on a common base; and,

Figure 4 is a fragmentary sectional view 50 of a modification.

The pump of my invention is free of end 55 thrust on the shaft 1, and consequently no end thrust bearing is necessary, the pump shaft 1 being connected directly to the motor shaft, and the pump and motor being mounted upon a common base, in line with each other.

The pump 3 is made up as shown in Figures 1 and 2, of two parts, namely, a front 60 plate 5, and a back plate 6, in which is housed the runner 7.

The casing formed of these two parts provides an outlet 8 at the upper end, surrounded by a flange 9, a portion of the 65 flange being formed on each plate. This

flange is adapted to be connected to a delivery pipe for the pump.

The two parts of the casing 5 and 6 have flanges 10 and 11 for bolting together the two parts of the casing in a well known 60 manner. The rear plate 6 provides the packing gland 13, which may be of any preferred or suitable character. At the lower portion of the plate 6 a foot member 14 is provided for mounting the pump, this 65 foot member being in the form of a plate disposed at right angles to the main portion of the plate 6, and being connected by a reinforcing web 15, which is disposed on the back side of the back plate 6. In a similar 70 manner, a flange 16 lies above the stuffing box 13, and connects the stuffing box with the back plate 6.

The front plate is provided with an inlet opening 17 having a bolting flange 18 about 75 the same, for attachment to a suitable intake pipe.

Between the plates 5 and 6 I provide a cylindrical peripheral space 20 communicating with the outlet 8 through a flared 80 discharge passage 21, which is most clearly illustrated in Figure 2. The peripheral space 20 provides a runway for the ends of the blades of the impeller 7, this impeller having, as shown in the present case, four 85 arms, the ends of which approach relatively close to the cylindrical surface of the space 20, providing only sufficient clearance to avoid rubbing against the cylindrical wall. This permits of a maximum length of impeller in a given size of pump casing. The 90 flaring passageway 21 opens into the space 20 with sufficient width to receive the discharge liquid, but to maintain a substantial seal of two of the pockets formed by the 95 impeller arms 22. In other words, the impeller arms define substantially quarters of the entire circumference of the pump, and the flared discharge passageway 21 also subtends substantially a quarter of the periphery. I intend that this discharge 100 passageway shall subtend a distance on the periphery of the casing not substantially less than the pitch distance between blades of the impeller.

Between the intake opening 17 and the peripheral space 20, I provide a conical pocket or intake passageway 23, which permits the liquid to attain a substantially radial direction before engaging the arms of 110

the impellers 7. This conical space 23 is not occupied by any part of the impeller, hence the incoming liquid is free to distribute itself freely through this space, and to lower its speed as compared with its speed on entering the opening 17. In the conical space 23 it is possible to dispose a screen, as indicated at 27 in dotted lines in Figure 1. This screen may be cast integral with the plate 5. The increased area provided by the diverging intake passageway 23 makes it possible to dispose the screen therein without restricting the flow.

There is no end thrust on the shaft 1, the incoming liquid apparently taking a radial course before it strikes the impeller. The impeller is provided with blades of the same width throughout their length, although I assume that this feature is not absolutely essential. However, the ends of the impeller arms 22 are substantially flat and straight, and fit fairly close to the side walls of the casings 5 and 6 where the space 20 is defined. In order to assist the dividing of the fluid radially, I provide in a modified form the directing cone 25, as shown in Figure 4, for leading the liquid radially to the ends of the impeller blade. This cone is supported by a number of arms 26, which may be cast integral with the cone 25 and the adjacent part of the casing 5.

I am unable to explain accurately the precise action which occurs inside the pump, but I am able to state as a result of a number of experiments that the present form of pump gives me greater efficiency than any form which I have previously constructed or found on the market. I find that the efficiency is higher than in any pump with which I am familiar. The pressure head which I am able to obtain with a given expenditure of power and a given rate of flow in a given size of pump, is higher with the present pump than any with which I am familiar. The pump does not become air bound upon the entry of air into the pump casing, and, as I have previ-

ously indicated, the pump will exert a suction even with air entering the casing.

What I assume from my experiments that occurs is the following: Liquid enters the opening 17 and spreads out throughout the conical space 23, assuming a relatively lower velocity, and taking a direction which is substantially radial with respect to the driving shaft 1. The vanes 22 of the impeller do not define closed pockets, but in their movement may tend to force the liquid radially into the space 20 by their throwing or centrifugal effect. This liquid is held outward by centrifugal gravity, is then thrown out at the flaring discharge passageway 21 by the centrifugal force which it has attained through the motion of the impeller arms and moves out through the discharge opening 8. At the same time, the incoming liquid tends to refill the pocket, and perhaps a portion of the incoming liquid tends to follow the discharge liquid out through the discharge passageway 21 being drawn outward by the velocity of the discharged or impelled liquid to carry with it a portion of the liquid directly from the intake passageway 23. The pocket is again filled or partially filled with liquid taken from the intake passageway 23, so that the real action of pumping occurs mainly at the upper half of the pump.

I am unable to say whether what I assume to occur does actually happen or not.

I do not intend to be limited to the precise details shown and described.

I claim:

A centrifugal pump having, in combination, rigid blades defining a whirling space bounded by parallel planes, an axial inlet, and a radial outlet opening directly into said space, said outlet having sides flaring into tangency with said space and subtending an arc of the periphery substantially equal to the arc between the tips of adjacent blades.

In witness whereof, I hereunto subscribe my name this 5th day of March, 1921.

HARRY E. LÀ BOUR.
